ORNAMENTING MACHINE

Benjamin W. Freeman, Cincinnati, Ohio

Application September 17, 1931, Serial No. 563,427
Renewed November 6, 1934

25 Claims. (Cl. 101—320)

This invention relates to shoe ornamenting machinery and more particularly to combined marking and cutting machines adapted for operation upon skins, upper blanks, fitted or closed uppers and the like, in which the work is marked with ink or the like at the same time, or as part of the cycle of operations during which the work is also ornamented by perforating or cutting out a design therein.

10 Among the objects of the invention are the formation of ornamental designs in the work, by the application of a stamped or printed marking which may simulate stitching or may take the form of a design, by the production of ornamental cutouts in the work, or by combinations of both, and in marking and cutting simultaneously, or during a continuous cycle of operations.

Another object contemplates the application of markings to the work which may be used as a 20 guide for subsequent operations, such as stitching, or aligning of the shoe parts with respect to the marked part.

Still another object resides in the provision of a marking device which will function as a stripper 25 in addition to its marking functions or a stripper arranged to function as a marking device in addition to its work stripping functions.

Various safety mechanism ensuring a predetermined cycle of operations and designed to prevent injury to an operator or to the work by preventing premature cutting operations form a 30 feature of this invention.

A further object contemplates the provision of a machine in which the work may be supported by either a flat bed or by an anvil adapted to 35 properly hold ring like work, such as closed and fitted uppers.

To the attainment of the above, and other objects which will appear as the description proceeds, reference may be made to the accompanying drawings, in which

Fig. 1 represents a front elevation of the machine;

Fig. 2 is a side elevation thereof;

Fig. 3 is a plan view of the work table;

Fig. 4 is a front elevation of the table;

Fig. 5 is a plan of the work supporting and positioning member;

Fig. 6 is a front elevation of the die unit;

Fig. 7 is a detail of the die unit;

Fig. 8 is a plan view of the die unit looking upward in Fig. 6; and

Fig. 9 is an enlarged detail section of the work supporting and position member illustrating a 55 modification of one of the marking dies of Fig. 6.

In a preferred embodiment of the invention illustrated herein there is disclosed a machine having a power driven plunger cooperating with a die unit (in the present embodiment the die is mounted on the plunger for movement therewith, although such die might readily be mounted independently of the plunger) and a work support on which the work is positioned, with a backing member of paper or its equivalent between the work and the support. In order to properly align, gauge and position the work, abutments are located on the work support although, a movable gauging mask might readily be utilized either in conjunction with, or in lieu of such an abutment.

Referring more specifically to the drawings, in which like reference numerals designate like parts, it will be observed that the machine comprises generally a base 10, supporting an upwardly extending frame or casing 11 within which are housed most of the movable operating parts. The head 24 of the frame 11 overhangs the forward portion of the base 10, on which portion is mounted an upright, anvil-like support 12. A pair of guide rails 13 and 14 are attached to the base 10 and are braced by struts 23, and upon which guides, a carriage or work table 15 is mounted for sliding movement. The running surface of the guide 13 is V-shaped, the carriage 15 being provided with a pair of correspondingly shaped rolls 16, and the guide 14 is formed with a T-shaped running surface, the carriage being provided with a pair of flat surfaced rolls 17 cooperative therewith. Removably attached to the table 15 is a work supporting and positioning plate 18. Positioning pins 19 extend from the upper face of the table, the plate 18 having holes 20 for cooperation therewith. When the plate and table are assembled, the openings 20 will be aligned with the pins 19 and the plate located and held thereby.

Openings 67 are formed in the plate 18, through which the cutting edges of the die may pass. The openings may be of such a size as to not only permit passage of the cutting edges of the die 4 therethrough, but also of such extent that the portion of the work to be marked may lie within the opening with the remainder of the work lying substantially flat on top of the supporting plate 18. The plate 18 will be made as thin as possible so that the work will not be depressed into the area 67 any more than is necessary. If desired either or both of the marking dies 38 and 39 may be made in two or more parts, operating independently at different levels (at the 55

time that the marking of the work takes place), to mark a portion of the work in the depressed area 67 and also to mark an adjacent portion of the work which is not depressed, as indicated in 5 Fig. 9.

The top of the support 12 may be provided with a sheet of brass to protect the cutting edges of the die and above this is mounted a sheet of paper 68, which is movable between a roll 69 located in the base of the machine and another roll 69' mounted adjacent the machine frame. The purpose of the paper or backing strip 68 is to contact with the cutting edges as they pass through the work to ensure clean cutting. The 10 operating mechanism at the left of Fig. 1, and manner of feeding the paper are substantially the same as described in a co-pending application Serial No. 515,346, filed February 12th, 1931.

With the work W (indicated as two quarters), 20 positioned and held on the plate 18, by means of a locating abutment 70 and spring clamps 71, the under portion of the work will occasionally strike the paper backing as the table is moved back and forward, the paper backing not being 25 shiftable with the table. This will not happen often, but in order to prevent such occurrence the openings 67 may be covered with a thin piece of tough material, which being fastened to the plate will prevent any frictional contact between 30 the work and the paper backing during the movement of the table or feed of the paper, if the work happens to be above the paper at that time. When the die comes down it will cut through the work and openings into this piece of material, 35 and it is only through these openings that there can be any contact between the work and the paper backing (or top of the support 12 in case no paper is used). The contacting surface is therefore reduced to a minimum, and to such a 40 small extent that it will substantially eliminate any frictional contact sufficient to cause movement of the work out of position, when the table is moved from work placing to work cutting position.

The table 15 and plate 18 are jointly movable from a position beneath the overhanging head 24, outwardly to an exposed location where they are freely accessible to the operator. Movement of the table may be effected manually, as shown 50 in Patent No. 1,681,033, or may be effected by the application of power suitably applied, an illustration thereof, being found in Reissue Patent No. 18,162 of August 25th, 1931.

Within the head 24 is mounted, for reciprocating movement, a plunger 25. This plunger is actuated by means of an arm 26 connected to a power shaft 28 which in turn may be connected by a single revolution clutch 29 to a continuously driven pulley 30, which serves as a means for supplying power to the machine. When the clutch 29 is operated, in a manner hereinafter described, to connect the pulley 30 and shaft 28, the shaft 28 will make one revolution, causing the plunger 25 to descend once and return, after which the plunger will remain in its inoperative position until the clutch is again actuated.

Attached to the plunger is a master die holder 32 carrying a pair of dies 33 and 34, which as illustrated, include a series of perforating or cutting tubes 35 supported by a die block or base member 36 detachably mounted in the master die holder 32. Supported in advance of the dies 33 and 34, respectively, are marking dies 38 and 39.

The marking dies are resiliently mounted on 75 the block 36 by means of pins 31 which extend

through openings 41 in the cutting dies 33 and 34, springs 37 serving to normally space the marking dies in advance of the cutting dies. A small cup-shaped collar 31' encircles each pin 31, and the pin 31 is held in position in its downward movement by means of a small pin 31' which is inserted in the pin 31 and enclosed within the cup-shaped portion of the collar. The spring 37 is located between the upper face of the cup-shaped collar and the block 26.

5 10

Referring particularly to Fig. 9 wherein is illustrated a marking die constructed to operate on work extending through different planes, it will be observed that either of the marking dies may be made in two-parts, 39' and 39''. The portion 39'' is illustrated as mounted over the depression 67, while the portion 39' will be effective to engage a part of the work not located over a depression.

15

The master die block is removably attached 20 to the plunger head by means of a dovetail rib 40 arranged to slide in a correspondingly shaped groove in the face of the plunger. Extending forwardly from this groove, through the plunger, is a shaft 42 having a handle 43 on its outer 25 end and a cam 44 on its inner end. When the holder is to be attached to the plunger, the rib 40 is placed in its groove and the cam shaft 42 partially rotated to wedge the rib in the slot, thus maintaining the holder rigidly in position.

30

The die block 36 is attached to the master die holder by means of a pin 45 having a V-shaped side face, and fitting into an opening of the holder, a cam shaft 47 having a manipulating handle 48 being provided for locking cooperation with the pin 45. A smaller pin 49 is also mounted on the block 36 and engages a hole in the holder, the pins 49 and 45 conjointly serving to locate and align the block with respect to the holder, the pin 45 additionally serving, through 40 its coaction with the lever 47, to lock the base or block 36 in its aligned position.

35

It should be observed that the base 36, the cutting or perforating dies 33-34 and the marking dies 38-39 form a unit which may be replaced in the holder 32 by other dies, to provide variations in the patterns and ornamentation which are to be applied to a shoe. While the unit illustrated comprises a pair of right and left dies, it may be desirable to have a single 50 pattern extending from one side to the other rather than a pair of right and left dies.

45

The marking dies 38 and 39 being mounted in advance of the cutting edges may have ink or other ornamenting material applied thereto such 55 as colored pigment, gold or silver leaf, etc., by any suitable means such as a hand pad, ink rollers or otherwise. In the present embodiment there is illustrated a movable roller 51 connected at its end to a pair of rack bars 52 arranged to be 60 driven by gear segments 53 through the medium of a pulley 54. This pulley is connected to and continuously rotated by the pulley 30.

65

A single revolution clutch 55 similar to clutch 29 is arranged to connect the pulley 54 to a shaft 56 which, through suitable linkage, will actuate the segments 53 to produce a single forward movement, of the rack bars and the roll past the marking dies 38-39 and back, applying the 70 marking medium to the dies.

75

Extending from the table 15 is a plate or finger 58 positioned to engage and control a clutch lock mechanism 59 which in turn controls a clutch key 60 adapted, in one position to prevent

75

actuation of the clutch 55 and in another position to release the clutch whereby the pulley 54 may be connected to the shaft 56. The clutch itself is actuated by means of a treadle rod 61.

5 The segments 53 are keyed to a shaft 62 on which is keyed an arm or lever 63. This arm is so located that as the segments reach a position in which they have fully retracted the ink roll 51 after an inking operation, the end of the arm 10 63 will engage a clutch lock mechanism 64 which controls a clutch key 65 adapted in one position to prevent actuation of the clutch 29 and in another position to release the clutch whereby the pulley 30 may be connected to the shaft 28. The 15 clutch itself may be actuated by means of a foot treadle rod (not shown) or may be arranged to automatically connect the pulley and shaft upon release by its key 65, the essential feature of this mechanism being, that the shaft 20 28 cannot be actuated by the continuously rotating pulley 30 until after the inking mechanism has completed its work and has been retracted, it being further observed that the inking mechanism cannot be actuated until the 25 carriage 15 has been located in operating position beneath the plunger and dies, which locating operation serves through the finger 58 to release the clutch 55.

Reference may be made to a co-pending application, Serial No. 478,264, filed August 27th, 1930, for a more complete description of the clutch arrangements and the operating mechanism for driving the plunger and ink roll, only such details as are essential, being described 35 herein.

The positioning or work supporting plate 18, as illustrated is made to support flat work and the embodiment of machine herein is designed especially to perform an ink marking and cutout operation on flat work. However, the support 12 is in the form of an anvil and obviously by use of a different style of work table 15 and plate 18 could be readily adapted to cutout and mark fitted work. As an example, a work support 40 of the general shape illustrated in the above mentioned application or patent might readily be substituted for the one illustrated herein, and it is contemplated that this machine may use a work support having top surfaces of any desired 45 size, area and shape necessary to accommodate same to a particular blank whether flat work or of the fitted upper type.

It is desirable that the work table be accurately held in position relative to the die and to accomplish this there is provided a block 72 on the work table which acts as an abutment for a lever 73, which presses against the block and clamps or holds the table and work in a very definite position with relation to the die, just before, during and immediately after the work cutting and marking operation. When the die, which is attached to the lower side of the plunger 25 moves down, the pin 74 which is resiliently mounted on the plunger also moves down; this pin is constantly in contact with a lever 75, mounted on a shaft 76 extending through the frame and the other end of which supports the lever 73. It will therefore be obvious that as the die moves downwardly the pin 74 depresses the lever 75 which in turn moves the lever 73 against the abutment 72. When the die reaches a position approximately a quarter of an inch above the work, the work table will be locked in position and will remain in that position until the die comes back up about 75 a quarter of an inch from the work. During

movement of the die into and out of contact with the work, the spring 77 permits the pin 74 to yield. The levers 73 and 75 will be maintained in normally upward position, contacting the pin, by means of the spring 78, and accordingly the lever 73 will be raised from the abutment 72 as the dies move upward, thus permitting free operation of the table 15.

If, instead of using a positioning plate 18, a mask or gauge such as in my application Ser. No. 478,264 is used, then a die positioning and locking mechanism as just described may be omitted. The abutment 72 and its coacting lever 73 are so shaped that if wear takes place in any of the parts or the operator fails to move the table all the way back, the abutment and lever will move the work holder into its proper position and in that position will hold it until the work has been marked and cut out.

From the foregoing description the operation 20 of the machine will be readily apparent. With the table in its outer position and removed from beneath the die the work is placed in proper position, and the table then pushed inward. The inward movement of the table unlocks the clutch 25 55 and the operator can then actuate the treadle rod 58 which will connect the gear segments 53 to the continuously driven pulley 54. The ink roll is thus moved forward and retracted to ink the marking edges of the die 38 and 39. Should 30 the operator's fingers for any reason be underneath the die at this time the forward movement of the ink roll will push them aside, in fact if desired a guard may be placed in advance of the roll for the sole purpose of sweeping away any 35 obstruction which might happen to come between the die and the work.

It has been pointed out that this machine is adapted to the use of other ornamenting materials than ink, examples of pigment, gold leaf, 40 etc., having been mentioned. The term "ink" as used in the specification and in the claims is intended to cover any such equivalent material.

The return movement of the ink roll releases the clutch 29, and the rotating pulley 30 is connected to the shaft 28, causing the plunger 25 to descend, pressing the dies against the work.

The marking dies will first contact the work and the cutting or perforating dies will follow, on continued downward movement of the plunger, 50 passing through suitable openings, illustrated in Fig. 8 as the space between the marking ribs 46, to cut out the desired ornamental pattern. Just before the marking die reaches the work, lever 73 and abutment 72 will coact to lock the work 55 table accurately in position.

The upward movement of the plunger completes a cycle of operations and the table may be again drawn outwardly for the insertion of a new piece of work.

On upward movement of the plunger which acts to draw the dies from the work, the cutting die will first be withdrawn from the work, the springs 37 serving to hold the marking plate against the work. The marking plate thus will 65 function as a stripper for the cutting dies in addition to its primary function of placing a marking on the work.

An advantage in the die structure, above described, and wherein the marker is resiliently 70 mounted, resides in the fact that need for adjustment of the marker is eliminated, inasmuch as need for pressure in marking is eliminated, this being due to the fact that no indentation as such is necessarily made in the work. Too much pres- 75

sure on the marker, which also functions as a stripper, will cut leathers. In known types of indenting markers, a spring tension sufficient to place an impression in the work is required and conventionally the stripper or marker of such type is usually provided with a rubber backing effective to distribute the pressure evenly. It is impossible to handle various thicknesses of leather, under such conditions, because if such a stripper is adjusted to indent a thick piece of leather, then insufficient pressure would be had to indent a thin piece. On the other hand, if the marker is adjusted to impress a thin piece of leather, then the pressure will be so great as to cut rather than merely indent greater thicknesses. In a similar manner, various types of leather or material used require different adjustments of the stripper, and in a good many instances regardless of adjustments, indentation cannot be satisfactorily accomplished. The net result, and use of such prior art devices is that different dies must be used for different thicknesses or types of material, or some adjustment must be made.

With the present invention the situation is entirely different. A conventional stripper mounting, using springs effective for one type and thickness of material is adapted to variant thicknesses, and the relation between the marker (or stripper) mounting and cutter, as disclosed herein, is adapted to various types and thicknesses of leather, because with the inked marking, in combination with cutting, no indentation of such is necessary, and hence a spring tension sufficient merely to strip is all that is required, no real pressure being needed in the application of ink, as distinguished from an impression or indenting marker.

Having thus described my invention, what I claim as new and desire to secure by Letters Patent of the United States, is:—

1. An ornamenting machine comprising a movable work support, a combined marking and cutting die unit, and means to apply ink to said die unit, pressure applying means for moving said die unit into ornamenting relation with a work piece on said support, means to accurately position said work relative to said die unit, means to actuate said pressure applying means thereby to ornament the work, and means operatively connecting said support, said ink applying means and said pressure applying means whereby movement of said die unit, said ink applying means and the work support are synchronized.

2. An ornamenting machine comprising a movable work support, a combined marking and cutting die unit, pressure applying means for moving said die unit into ornamenting relation with a work piece on said support, means to apply marking material to said die unit, and means to actuate said work support, ink applying means and said pressure applying means in predetermined synchronized relation.

3. An ornamenting machine comprising a movable work support, a combined marking and cutting die unit, having cutting edges and a marking member spaced in advance of said cutting edges, pressure applying means for moving said die unit into ornamenting relation with a work piece on said support, means to apply ink to the marking member, and means to actuate said work support, ink applying means and said pressure applying means in predetermined synchronized relation.

4. An ornamenting machine comprising a work

support, a combined marking and cutting die unit, pressure applying means for moving said die unit into ornamenting relation with the work piece on said support, means mounting said support for movement into and out of operative position relative to said pressure applying means, means to apply a marking medium to said die, means to actuate said pressure applying means thereby to ornament the work, and means controlled by said medium applying means to restrain said pressure applying means from actuation until said medium applying means has completed its portion of the cycle of operation.

5. An ornamenting machine comprising a movable work support, a combined marking and cutting die unit, and means to apply ink to said die unit; pressure applying means for moving said die unit, means controlled by said support for initiating actuation of said ink applying means, when said support is moved to a predetermined position, and means for actuating said pressure applying means thereby to ornament the work.

6. An ornamenting machine comprising a movable work support, a combined marking and cutting die unit, and means to apply ink to said die unit; pressure applying means for moving said die unit, means controlled by said support for initiating actuation of said ink applying means, when said support is moved to a predetermined position, means for actuating said pressure applying means thereby to ornament the work, and means controlled by said ink applying means for initiating actuation of said pressure applying means when said ink applying means is moved to a predetermined position.

7. An ornamenting machine comprising a movable work support, a combined marking and cutting die unit, and means to apply ink to said die unit; pressure applying means for moving said die unit, means for actuating said pressure applying means thereby to ornament the work, and means controlled by said ink applying means for initiating actuation of said pressure applying means when said ink applying means is moved to a predetermined position.

8. A machine for ornamenting shoe parts comprising a movable support, means to properly position a piece of work on said support, a cutting die and a stripper having marking elements thereon, means to apply ink to said marking elements, means to advance and retract said ink applying means to and from operative position, and means automatically actuatable by said support to initiate movement of said ink applying means.

9. A machine for ornamenting shoe parts comprising a movable support, means to properly position a piece of work on said support, a marking die and a cutting die, means to apply ink to said marking die, means to advance and retract said ink applying means to and from operative position, and means to lock the inking means against movement, and means automatically actuatable by said support to release said locking means.

10. A machine for ornamenting shoe parts comprising a movable support, means to properly position a piece of work on said support, a marking die and a cutting die, means to apply ink to said marking die, means to advance and retract said ink applying means to and from operative position, means automatically actuatable by said support to initiate movement of said ink applying means, and means automatically actuatable by

- said inking means to initiate movement of said die toward the work.
11. A machine for ornamenting shoe parts comprising a movable support, means to properly position a piece of work on said support, a marking die and a cutting die, means to apply ink to said marking die, means to advance and retract said ink applying means to and from operative position, means to move said die toward the work, means to lock said die moving means in an inoperative position until actuated by said inking means, and means automatically actuatable by said inking means to release said locking means.
12. A machine for ornamenting shoe parts comprising a movable support, means to properly position a piece of work on said support, a marking die and a cutting die, means to apply ink to said marking die, means to retract said ink applying means from operative position, means to move said die toward the work, means to lock said die moving means in an inoperative position until actuated by said inking means, means to lock said inking means against movement, and means automatically actuatable by said support to release said last named locking means.
13. In a machine for ornamenting shoe parts, a movable work support, having an opening for the passage of a die therethrough, and a combined marking and cutting die unit, means to position a work piece on one side of said support, over said opening a backing member arranged adjacent the opposite side of the support and across said opening, said member and support being relatively movable during machine operation, means on said support effective to space the work out of frictional contact with said backing member during movement of the support, and pressure applying means effective to produce a relative movement between said die unit and said work support thereby to ornament work on said support.
14. In a machine for ornamenting shoe parts, a movable work support having an opening for the passage of a die therethrough, and a combined marking and cutting die unit, means to position a work piece on one side of said support, over said opening, a strip of paper forming a backing member located for movement adjacent the opposite side of the support, said member and support being relatively movable during machine operation, said support having a sheet of material partially covering the opening to space the work out of frictional contact with said member during movement of the support and of the member, and pressure applying means effective to produce a relative movement between said die unit and said support thereby to ornament work on said support.
15. A combined marking and cutting die unit comprising a master die holder, a die block detachably mounted thereon, a plurality of independent cutting dies mounted on said block, a plurality of marking dies respectively mounted thereon in advance of said cutting dies, said marking dies being resiliently mounted independently of said cutting dies and for movement relative thereto.
16. An ornamenting machine comprising a movable work support, a combined marking and cutting die unit comprising a master die holder, a die block detachably mounted thereon, a plurality of independent cutting dies mounted on said block, a plurality of marking dies respectively mounted thereon in advance of said cutting dies, said marking dies being resiliently mounted for movement relative to said cutting dies, pressure applying means for moving said die unit into ornamenting relation with a work piece on said support, means detachably connecting said master die holder and said pressure applying means, and means to actuate said work support, ink applying means and said pressure applying means in a predetermined synchronized relation.
17. An ornamenting machine comprising a movable work support, a cutting die, a stripper plate therefor having marking elements thereon, and means to apply ink to said marking elements, pressure applying means for moving said die and stripper into ornamenting relation with a work piece on said support, means to accurately position said work relative to said die and stripper, and means to actuate said pressure applying means thereby to first ornament the work and thereafter strip the work from the cutting die.
18. An ornamenting machine comprising a movable work support, a cutting die, a stripper plate therefor having marking elements thereon, and means to apply ink to said marking elements, pressure applying means for moving said die and stripper into ornamenting relation with a work piece on said support, means to accurately position said work relative to said die and stripper, and means to actuate said pressure applying means thereby to first ornament the work and thereafter strip the work from the cutting die and means operatively connecting said support, said ink applying means and said pressure applying means whereby movement of the die, the work applying means and the work support are synchronized.
19. A machine for operating upon shoe parts, comprising a movable work support upon which the work is positioned during operations on the work, means to align a piece of work on said support in proper operating position, a marking die mounted in spaced relation to said support, releasable mechanism for actuating said marking die, means to apply ink to said marking die, mechanism, releasable independently of said die actuating mechanism, for actuating said ink applying means, said ink applying means being movable and operable independently of movement of said die, and means to initiate movement of said marking die toward the work.
20. A machine for operating upon shoe parts, comprising a movable work support upon which the work is positioned during operations on the work, means to align a piece of work on said support in proper operating position, a marking die mounted in spaced relation to said support, releasable mechanism for actuating said marking die, means to apply ink to said marking die, and mechanism, releasable independently of said die actuating mechanism, to move said ink applying means into and out of operative relation to said die independently of movement of said work support.
21. A machine for operating upon shoe parts, comprising a movable work support upon which the work is positioned during operations on the work, means to align a piece of work on said support in proper operating position, a marking die mounted in spaced relation to said support, releasable mechanism for actuating said marking die, means to apply ink to said marking die, mechanism, releasable independently of said die actuating mechanism, to move said ink applying means into and out of operative relation to said die independently of movement of said work support.

die independently of movement of said work support, and means to synchronize movements of said work support and ink applying means with respect to each other.

- 5 22. A machine for operating upon shoe parts, comprising a movable work support upon which the work is positioned during operations on the work, means to align a piece of work on said support in proper operating position, a marking die mounted in spaced relation to said support, releasable mechanism for actuating said marking die, means to apply ink to said marking die, mechanism, releasable independently of said die actuating mechanism, to move said ink applying 10 means into and out of operative relation to said die independently of movement of said work support, said ink applying means being movable and operable independently of movements of said die, and means to synchronize movements of said work support, die and ink applying means with respect to each other.

- 15 23. A machine for operating upon shoe parts, comprising a movable work support, a marking die mounted for movement relative to said work support, ink applying means for said die movable into and out of engagement therewith, said support, die and ink applying means being independently movable in synchronized relation with re- 20

spec to each other, and means operable after said ink applying means completes a cycle of operations, to initiate actuation of said die.

24. A machine for operating upon shoe parts, comprising a laterally movable work support, a movable marking die mounted in spaced relation to said support, means to apply ink to said marking die, said ink applying means being movable and operable independently of movement of said die and of said work support, and means to initiate movement of said marking die toward the work, and means to lock said support in operating position during movement of said die. 10

25. A machine for operating upon shoe parts, comprising a laterally movable work support upon which the work is positioned during operations on the work, a movable marking die mounted in spaced relation to said support, means to apply ink to said marking die, said ink applying means being movable and operable independently of movement of said die, means to initiate movement of said marking die toward the work, and means to restrain said marking die from movement until said work support is positioned in aligned, operative position with respect to said die, and means effective thereafter to lock said support in aligned position until said die completes its cycle of operations. 15 20 25

BENJAMIN W. FREEMAN.
